UNITED STATES PATENT OFFICE

AUGUST DE FREITAS, OF HONOLULU, TERRITORY OF HAWAII

AMUSEMENT DEVICE

Application filed April 19, 1929. Serial No. 356,461.

This invention relates to amusement devices and more particularly to a combined merry-go-round and see-saw.

An object of the invention is to provide a device of this character which may be conveniently used on play grounds, beaches as well as private homes.

Further the invention provides an amusement apparatus whereby a plurality of persons may oscillate or see-saw and at the same time revolve about a vertical axis.

With the preceding and other objects and advantages in mind, the invention consists in the novel combination of elements, constructions and arrangements of parts and operations to be hereinafter more fully described, claimed and illustrated in the accompanying drawings, wherein:

Figure 1 is a perspective of the invention; 20 Fig. 2 is a view partly in vertical section and partly in elevation;

Fig. 3 is a horizontal section taken on line 2—2 of Fig. 2.

Referring to the invention in detail a base 25 is provided which consists of upper and lower horizontally disposed discs 5 and 6 connected together by spaced vertical slats 7. The base is reinforced at its lower end by a circumferential band 8 extending around the lower 30 ends of the slats and the disc 6.

A turntable 9 is revoluble on the disc 5 and carries a depending annular flange 10 which skirts the disc 5. Anti-friction elements such as rollers 11 are attached to the 35 under face of the turntable at the center of the latter and adjacent its other edge. Openings 13 are formed in the turn table above the rollers to afford clearance for the latter. These rollers 11 are revoluble on circular 40 track ways or wear strips 14.

A revoluble post 15 passes centrally through the base and turntable. At its lower end the post is formed with a reduced part 16 which is revoluble in a central opening 17 in the disc 45 6. A key 18 extends transversely through

the reduced part to hold the post against vertical displacement. To reduce friction at the lower end of the post a bearing race 19 is received on the reduced part above the disc 6 and contains bearing balls 20 which contact with a shoulder on the post afforded by the reduced end.

The post extends a considerable height above the turntable and is formed with a bore or socket 21 for the reception of the 55 shaft of a suitable sun-shade or parasol 22. In practice the post and turntable rotate together and for this purpose these parts are rigidly connected by suitable angle brackets 23. These angle brackets are of such strength 60 as to rigidly support the post.

The lower portion of the post is enclosed in a rectangular housing 23 built within the base. Thus dirt, sand and other foreign matter cannot come in contact with the bearing 65 balls when the apparatus is used out of doors.

Arranged above the turntable in intersecting relation is a pair of passenger carrying boards or see-saws 24. Each of the boards 24 is provided with a central rectangular opening 25 through which the post 15 passes. Inverted U-shaped hand grips 26 extend from the upper face of each of the boards and are located at either side of the post.

In order to pivotally support the boards 75 shafts 27 extend transversely through the post and are embraced by transversely aligned bearings 28 attached to the under face of each board.

In the operation of the invention the turntable is rotated by an attendant who successively pushes against the occupants of the see-saws. At the same time the occupants of each see-saw alternately push against the turntable to impart rocking motion to the 85 see-saws.

What is claimed is:

In an amusement device a circular elevated base, a disk arranged parallel to the base slightly above the latter, anti-friction ele- 90

ments depending from the underface of the disk and having rolling contact with the base, a circular flange depending from the edge of the disk and overlying the outer edge of the base, a vertical post extending centrally through the base and disk, means for securing the disk to the post, a bearing for rotatably supporting the lower end of the post, and passenger carrying beams pivotally supported on the post above the disk.

AUGUST DE FREITAS.
